CORE-EXTRACTING DEVICE.

Application filed July 17, 1923. Serial No. 652,120.

This invention relates to a device for extracting a core from a core-barrel. Such core-barrels are used in deep well drilling operations in order to enable the samples of 5 the strata to be taken for inspection by the driller. It is desirable, if possible, to deliver the core to the driller intact as taken by the core barrel of the drill; that is to say, without breaking up the core or disturbing 10 the relation of its parts, to the end that the core, after extraction from the barrel, will show the natural relation of the strata, sand or earth through which the core drill is passed.

15 The general object of this invention is to produce a device for extracting a core from a core-barrel which will enable this desirable result to be achieved, and which can be simply applied to a core-barrel and simply 20 operated to discharge the core from the barrel, and without disintegrating or breaking up the core.

Further objects of the invention will appear hereinafter.

25 The invention consists in the novel parts and combination of parts to be described hereinafter, all of which contribute to produce an efficient core extracting device.

A preferred embodiment of the invention 30 is described in the following specification, while the broad scope of the invention is pointed out in the appended claims.

In the drawing:

Figure 1 is a longitudinal section taken 35 through a core-barrel and illustrating a preferred embodiment of the invention; the view shows the device in operation with the core partially expelled from the barrel.

Figure 2 is a longitudinal section upon an 40 enlarged scale passing through the end of the core-barrel at which the extracting plunger enters, and particularly illustrating details of the construction for connecting the plunger-head to the plunger-rod.

45 Figure 3 is a cross-section taken at the position of the line 3—3 of Figure 2, but passing only through the plunger-head and plunger-rod to further illustrate details of the construction.

50 In practicing our invention, we provide a member with means for attaching it to the core-barrel, and this member carries a

plunger which is movable within the barrel for forcing the core out of the other end of the barrel. The member which is attachable 55 to the core-barrel may be of any suitable construction, but we prefer to construct it in the form of a simple head or plug 1 which is provided with threads 2 at its inner end to mesh with similar threads 3 which 60 are formed at one end of the core-barrel 4. Through this member 1 the plunger 5 is guided to move so that it can pass through the interior of the core-barrel and force the core 6 out of the other end. The plunger 65 comprises a stem or rod 7 which is mounted in any suitable manner in the plug to enable it to be advanced through the plug when in operation. We prefer to form this rod 7 in the form of a feed-screw by providing it 70 with threads 8 which engage with the correspondingly threaded opening 9 in the plug.

As this construction will necessarily involve a rotation of the stem or rod 7, we provide means at the inner end of the rod which 75 will engage the inner end of the core without rotating, and for this purpose we construct the inner end of the plunger in the form of a swivel-head 10 which is connected to the end of the rod 7 in any suitable manner which will enable a swiveling movement to take place, that is to say, which will enable the plunger 5 to engage the core without rotating, but at the same time permitting 80 free rotation of the rod 7 as it advances through the plug to force the core out of the other end of the barrel.

For this purpose, we provide the plunger with an annular groove 11 beyond the threads 8 which do not extend to the extreme end of the rod. In this way a plain cylindrical tip is formed 85 on the end of the plunger-rod, and this tip is received in a corresponding recess or bore 12 formed in the head 10. And we provide means in the form of a cotter-pin or pins 13 which are driven into drilled holes 14 in the head located so that the pins pass through the groove 11 on opposite sides of the axis 90 of the rod.

It should be understood that these pins do 100 not have to take the thrust of the rod against the head, but are merely for effecting the swivel connection between these two parts.

In order to impart the thrust from the

rod to the head, we provide an anti-friction device, such as a ball 15, which engages a dished bottom 16 formed at the inner end of the bore 12, and a cup-shaped recess 17 formed in the end of the rod. This ball should be formed of hardened steel so that it will transmit a considerable force at the same time it offers very slight frictional resistance to the rotation of the plunger relatively to the head.

Any suitable means, such as a double-lever 18 with handles 19, may be provided for rotating the plunger-rod 7.

In practice, the threads 2 of the plug 15 would be made to fit the standard threads 3 which are found at the end of the core-barrel, and hence no special means is necessary for attaching the member or plug 1 to the end of the barrel.

It will be evident that by rotating the lever 18 a considerable force can be exerted upon the swivel-head 10 which will operate to force the core out of the core-barrel, and as the head rotates freely on the plunger-head 7 it can engage the end of the core without rotation. Therefore, it will not have any tendency to disintegrate the core, but will merely shove the core as a whole out of the end of the barrel. In this way, if the core is carefully extracted, its particles will remain in the same natural relation which they had in the ground from which they were taken by the drill.

It is understood that the embodiment of the invention described herein is only one of the many embodiments this invention may take and we do not wish to be limited in the practice of our invention nor in our claims to the particular embodiment set forth.

What we claim is:

1. In a device for extracting a core from a core-barrel having a threaded end, the combination of a plug having threads to enable the same to be secured to the threaded end of the barrel, and a plunger having a rotatable rod guided through said plug and having a swivel-head for engaging the core to enable the core to be forced out of the other end of the barrel, said swivel head operating to engage the core without rotating, and thereby prevent breaking up the core.

2. In a device for extracting a core from a core-barrel having a threaded end, the combination of a plug having threads to enable the same to be screwed onto the end of the barrel, and a plunger having a threaded rod passing through said plug, having a handle for rotating the same to advance the plunger through the barrel, and a swivel head carried by the inner end of the plunger-rod to engage the core for forcing the same without rotating it out of the other end of the barrel.

3. In a device for extracting a core from a core barrel, the combination of a member having means for attaching it to the core barrel, a plunger carried thereby having a rod threaded in said member and operating to move when rotated in the barrel, a swivel-head having means therein engaging the end face of the rod for imparting the thrust of the rod to the head, and means for attaching the head to the end of the rod, permitting a free swiveling movement of the head on the rod.

4. In a device for extracting a core from a core-barrel, the combination of a member having means for attaching it to the core barrel, a plunger having a rod threaded through the member and operating to move through the barrel when rotated, said rod having a circumferential groove adjacent the inner end thereof, and a head rotatably mounted on the end of the rod and having a cotter received in said groove for connecting the same so as to swivel on said rod.

5. In a device for extracting a core from a core-barrel, the combination of a member having means for attaching it to the core barrel, a plunger having a rod guided through the member and movable through the barrel, said rod having a circumferential groove adjacent the inner end thereof, a head rotatably mounted on the end of the rod and having a cotter received in said groove for connecting the same, so as to swivel on said rod, and a ball carried by the head and engaging the end of the rod to impart thrust from the rod to the head.

Signed at Torrance, California, this 7th day of July, 1923.

GEORGE IRVIN KENISTON.
CHARLES ERNEST PRIESTLEY.
